BINDER AND RING USABLE THEREIN

John J. Seelman, Milwaukee, Wis., assignor, by direct and mesne assignments, to Geo. Seelman & Sons Co., Milwaukee, Wis., a corporation of Wisconsin

Substituted for abandoned application Serial No. 446,163, June 8, 1942. This application February 8, 1943, Serial No. 475,097

14 Claims. (Cl. 129—1)

This invention relates to improvements in binders and rings usable therein, the application for which is a substitute for application Serial No. 446,163 filed June 8, 1942.

It is the primary object of the invention to provide a neat, simple, durable, and inexpensive binder and binder ring with provision for rigidly mounting the improved binder ring in the cover and for accommodating different thicknesses and conformations of cover.

More specifically stated, it is one of the primary objects of the invention to provide a plastic binder ring of a type having oblique slots for the manipulation of the loose leaf sheets to and from the respective rings, and having constructional features inherently protecting the split ends of the ring against breakage and against "cold flow" under weight. The protection of the ring against breakage and deformation is partially attributable to the formation of the binder ring itself and partially attributable to the relation of the binder ring to the binder back and covers. Extending completely across the backbone of the binder in the interior thereof between the covers, is the relatively heavy base of the binder ring, amply able to withstand all pressure transmitted from one cover toward the other. From this base crescent-shaped arms extend upwardly and preferably are curved across the base in substantially the arc of a circle, gradually diminishing in cross section. Where they join the base the inner surfaces of such arms are preferably curved inwardly, while the outer surfaces of such arms are preferably approximately normal to the top edge of the base. It will be seen that the whole constitutes a modified crescent, the modification consisting of a flattening of the crescent base. This not only provides strength but also enables the top edge of the base to limit the downward movement of the paper sheets upon the arms, thereby preventing the sheets from weighing or tearing as would occur on an unmodified crescent form, a very important feature of the present invention.

It is a further specific object of the invention to provide a plastic type binder ring with a complementary plastic anchorage member, such ring and member being relatively adjustable to accommodate different thicknesses of binder backs and being readily adapted to be secured in adjustment by a non-metallic fastening means.

Various other objects of the invention will be apparent to those skilled in the art upon the following disclosure thereof.

In the drawings:

Fig. 1 is a view in perspective fragmentarily il-

lustrating a binder back equipped with rings in accordance with this invention.

Fig. 1a is a detail view in cross section through a binder with a curved backbone illustrating in side-elevation one of my improved binder rings in its proper association with the binder.

Fig. 2 is a view in perspective of the exterior of the back showing the closed portions of the binder ring anchorage members.

Fig. 3 is a fragmentary detail view in cross section through the back and one of the rings.

Fig. 4 is a detail view in perspective showing the separated ring and anchorage member.

Fig. 5 is a view in perspective showing the component parts of a modified ring and anchorage member assembly.

Fig. 6 is a fragmentary view in cross section through a binder back illustrating the device of Fig. 5 as it appears when assembled.

Fig. 7 is a view similar to Fig. 5 showing a further modified embodiment of the invention.

Fig. 7a is a detail view in plan of the retainer shown in Figs. 7 and 8.

Fig. 8 is a view similar to Fig. 6 showing the device of Fig. 7 as it appears when assembled.

Fig. 9 is a view similar to Fig. 5 showing a further modified embodiment of the invention.

Fig. 10 is a view similar to Fig. 6 showing the device of Fig. 9 as it appears when assembled.

Fig. 11 is a view similar to Fig. 10 showing in assembly a further modified embodiment of the invention, the back of a binder being fragmentarily illustrated.

Fig. 12 is a detail view in plan showing how the tips of the plastic arms of any one of the binder rings herein disclosed may be deflected into interlocking engagement.

Like parts are identified by the same reference characters throughout the several views.

The binder shown in Fig. 1 is of generally conventional form, apart from the rings and the manner in which they are mounted therein. There is the usual "backbone" 15 to which a pair of covers 16 and 17 are hingedly connected. In practice the backbone 15 may show considerable variation in thickness in different binders, and accordingly it is desirable that my improved binder ring and its anchorage device should accommodate backbones which vary materially. The backbone may be either flat in cross section (Fig. 1) or curved (Fig. 1a).

The binder ring in its preferred form is of a modified crescent form, as clearly shown in Figs. 1 and 4. It comprises a relatively heavy base portion 18 having a lower margin 19 preferably

rectilinear at least in its central extent for engagement with flat "backbones" 15. The base is preferably beveled at 14, however, to adapt it for use in concave backbones such as that shown at 150 in Fig. 1a. Such backbones are very common. The upper margin 20 of the base may be rectilinear, as indicated in Figs. 1 and 4, or it may arch convexly upwardly, as shown in Fig. 5 at 200.

Formed integrally with the base 18 are the arms 21 and 22 which constitute the binder ring. Externally the surfaces of arms 21 are either parallel with each other and substantially normal to the base, or may be slightly convergent upwardly away from the base.

Their inner surfaces, however, preferably diverge from each other upwardly of the base as clearly appears in Figs. 1 and 1a. The resulting crescent-shape of the respective arms gives them great strength, particularly adjacent the base, where bending moments are greatest. It might appear that due to the fact that the cross section of the arms increases toward the base, sheets of paper engaged thereon might become wedged on the arms or tend to tear when pulled upwardly. This is prevented by the construction best shown at Fig. 1a, wherein it will be noted that the sheet 12 is supported by the base margin 20 at a level at which the relative dimension of the hole in the sheet, respecting the cross section of the arm, is such that no wedge can occur. Moreover, when the sheet is lifted toward the point of discharge from the ring, it is immediately moved toward a portion of the arm which has a small cross section, thereby freeing it at once from any possible tendency to wedge.

Particularly where a curved backbone 150 is employed (Fig. 1a), the hinged joint between the backbone and the cover is brought up closer to the level of the top margin 20 of the base of the binder ring, so that the lowest sheet, such as that shown at 12, will lie almost flat against the cover, close to the ring. This result is achieved despite the fact that the base portion 20 of the ring is preferably located within the backbone and between the covers to take up pressure and to relieve the arms of the ring therefrom. Fig. 1a shows how the cover 17, in its closed position, extends upwardly in substantial contact with the arm 22 of the ring.

The extremities of the arms are finished in approximate parallelism in spaced oblique planes to provide an intervening oblique slot 23 through which the loose leaf sheets of the binder may be manipulated in a well known manner.

It is characteristic of all of the split ring devices herein disclosed that in each instance the relatively heavy base 18 represents the greatest width of the split ring and the arms 21 and 22, or their equivalent, progressively approach each other curvilinearly from some point at or above the base 18. The construction described is particularly desirable where plastics are used. It would, however, also be desirable if the ring were made of metal. The reason may not at first be apparent.

In shipment, storage, and otherwise, binders of this type are frequently subjected to heavy loads. It is found that where the arms 21 and 22 bow outwardly beyond the base to which they are connected, any substantial load imposed thereon will either crack off such arms (if they are made of plastic or the like), or will permanently deform them owing to the fact that the resilience of a plastic and even of a metal, may be overcome

by "cold flow" which occurs under long continued pressure even though such pressure is wholly inadequate to strain the material beyond the elastic limit if the pressure is continued only for a short time. This is also true of D-shaped rings in which all parts are of equal thickness and thin enough to be usable with paper having standard size apertures. I have found it very desirable, particularly where plastics are used, to provide the modified crescent shape with the heavy base 18 which represents the maximum dimension of the device.

Moreover, it will be noted that I locate this heavy base between the covers where it is in a position to take the load, and I make its length approximately equal to the transverse dimension of the backbone so that the hinges between the covers and the backbone are located approximately at the corners of the base of each ring.

The anchorage member 25 and the ring member above described, are preferably in adjustable connection to allow for varying thicknesses of the cover backbone element 15. I have found it convenient to provide for adjustable connection of the parts by telescopically relating them as best shown in Fig. 3. This may conveniently be done by forming a non-circular block 26 integral with the base member 18 of the ring element and providing the anchorage member 25 with a socket at 27 into which the block 26 is receivable with a sliding fit. The socket 27 is extended in part into the solid material of the anchorage member 25 and it is formed in part by a pair of mutually spaced C-shaped outstanding flanges 28 and 29 constituting an outward extension of the socket 27. When the block 26 is received between the flanges 28 and 29 and into the socket 27, the base 18 may enter between the flanges 28 and 29, as clearly appears from Fig. 4.

Externally the anchorage members may be faceted for ornamentation as shown in Fig. 2.

Each of the anchorage members comprises a plate-like flange at 30 which abuts the cover backbone externally. It will be noted that preferably the greatest dimension of this plate-like flange is vertical with respect to the cover.

The inner surface of a flat backbone is abutted by the edge 19 of the base member 18 of the ring element. The surface 19 extends transversely of the backbone and hence substantially at right angles to the direction of extent of the flange 30. The engagement of the backbone by these two surfaces at right angles to each other provides great stability, and the fact that the block 26 is non-circular (in practice preferably rectangular) in cross section assures against any rotative displacement of the ring element with respect to the cover when the device is in use. It is desirable to preclude any possibility of rotative displacement because the facility with which the sheet may be manipulated through the oblique slot of the ring element may depend upon the stability of the ring element.

It will be apparent that the telescopic connection of the anchorage element and the ring element permits these parts to be secured to each other to be effective in quite a substantial range of relative adjustments. Preferably, some one of the numerous plastic adhesives or solvents is used, the exact choice of solvent or adhesive depending, in many instances, upon the particular material of which these elements are composed. An adhesive, however, will permit of the permanent connection of the telescopically related parts 75 without requiring the use of any metal. The close

Sliding fit of the block 26 between the flanges 28 and 29 and into the socket 27, facilitates the operation of the adhesive in assuring a tight joint. In the construction shown in Figs. 5 and 6 the anchorage member 250 substitutes a pair of outstanding ears 280 and 290 for the flanges 28 and 29 of Fig. 4. These ears project sufficiently so that no block is required on the base 180 of the ring element here shown. Instead, the said base 180 is apertured at 31 in registry with aligned apertures 32 and 33 in the respective ears. When the base 180 of this ring element is pressed against the backbone 45 of a known dimension for which it has been designed, the several holes 31, 32 and 33 will be brought into alignment to receive a pin 35 which may depend upon friction for its retention or may be adhesively secured in place. The broad flat face 300 of the anchorage member 250 engages the outside of the cover while the margin or edge 19 of the base portion 180 of the ring element engages the inner face of the cover to secure the ring rigidly in position. The opening made in the backbone will be rectangular to conform to the cross sectional outline which is the combined result of the ears 280 and 290 as shown in Fig. 6, thus securing the ring against torsional displacement.

In the construction shown in Fig. 7 the base portion 181 of the split ring element has a tab at 36 projecting from its margin 191, leaving shoulders at 37 to engage the inner face of the backbone of the binder. The tab has an opening at 38 which may be trapezoidal in form, to receive retainer 40 which may be tapered at both ends to facilitate its introduction and provided at 41 with two slight elevations spaced to receive the tab between them. The cross piece of tab 36 beyond the opening 38 has sufficient resilience so that it will yield slightly at its center to permit one of the projections 41 to be forced beneath it. Thereupon it will spring back into position between the projections 41, which are so spaced as to receive it substantially exactly, thereby anchoring the retainer 40 in position to secure the ring in the binder.

In the construction shown in Figs. 9 and 10 the arrangement is quite similar to that shown in Figs. 3 and 4. The anchor member 252 has a plate-like flange 302 and a socket 272 surrounded by a box-like flange 282 in which the block portion 262 of the split ring element is received. At the level of the margin 192 of the base portion 182 of the split ring element, the block portion 262 is surrounded by a flange 42 which, in the assembly, covers the opening in the backbone member 15, as clearly shown in Fig. 10, as well as increasing the seat provided between the backbone and the ring element.

In the construction shown in Fig. 11 three additional features are illustrated which are each individually adapted for use with each other or interchangeably, with the other constructions shown. One of these features comprises the use of an anchorage strip 253 which extends continuously along the backbone to serve all of the ring elements mounted thereon instead of requiring separate anchorage bases for each ring element. As a second feature it is preferably, though not necessarily, on the inside, cemented to the backbone and thus avoiding any exterior projection. Another feature consists in the provision of two separate studs at 43 which are socketed in the widened base 183 with which the ring element is provided. As in the construction shown in Figs. 1 to 4, 9 and 10, the anchorage device and the ring

element are adhesively joined in this construction. It will, of course, be understood that either the anchorage strip, or the use of separate retaining studs, or the use of an interior anchorage, may be used independently of the other features or in conjunction with any of the other constructions when desired.

In all embodiments the base preferably is as wide as any portion of the ring element and is located within the back and between the covers, with crescent shaped arms springing from it to comprise the split ring as above described. The crescent shape of the arms is a very important feature of the invention in actual practice.

Since the plastic or metal employed will preferably have considerable resilience which progressively increases toward the tips of the arms, it is possible to interlock the tips of arms 21 and 22 by manipulating them past each other from the position shown in Fig. 1 to that shown in Fig. 12, whereupon their tips will engage to prevent a return to the original positions until they are so manipulated that they are moved vertically as well as laterally. In this interlocked position of the arm tips it will be found that the sheets will slide freely from one arm to the other but cannot escape from the ring until the arms are released by manipulation back to the Fig. 1 positions thereof.

It is noteworthy that unlike some previous split ring binders, it is possible to utilize in the present device the full width of the backbone without subjecting the split rings to breaking or deforming pressures. This gives the device of my invention added capacity since the split rings have increased width. When the covers are folded as shown in Fig. 2 they will substantially contact the sides of the base portions 18 of the respective ring elements but, in so doing, substantially all strains will be transmitted directly to the base portions of the ring elements and the arms comprising the split ring will, in each instance, be sufficiently relieved of strain by their curvilinear form so that despite the use of plastic in their construction, they will neither crack nor be deformed under load.

I claim:

1. In a loose leaf book back having a backbone and covers, the combination with an anchorage member applied externally to the backbone and a split ring element applied internally to the backbone, of means connecting said member and element with each other through the backbone, said connecting means comprising telescopically slidable parts projecting respectively from the member and the element, whereby said means is adjustable to maintain such connection through backbones of differing thickness.

2. In a loose leaf book having a backbone and covers, the combination with an anchorage member applied externally to the backbone, a split ring element applied internally to the backbone, and means connecting said member and element with each other through said backbone, said connecting means comprising parts respectively connected with the member and element and in telescopic engagement with each other, said parts being adhesively joined.

3. A split ring for use in a loose leaf binder, comprising a base and a pair of crescent shaped arms thereon, each of said arms progressively decreasing in cross section upwardly away from said base and said base comprising means limiting the movement of apertured paper sheets downwardly upon the respective arms, the out-

side surfaces of the arms being substantially parallel adjacent the base and the inside surfaces of said arms being outwardly divergent in projecting from said base.

4. A split ring for use in a loose leaf binder comprising a base and a pair of arms mounted on the base and extending curvilinearly toward each other at a point remote from the base, said arms being oppositely beveled adjacent their respective tips and the tips normally lapped in spaced relation, at least one of the arms being sufficiently resiliently flexible to permit of the manipulation of its tip to the opposite side of the tip of the other arm, whereby such tips are interlocked to provide a closed ring from one arm of which to the other paper sheets are readily slideable across the interlocked tips.

5. A split ring device for use in ring type binders, said device comprising a ring element having a base portion engageable with the inner face of a backbone, an anchorage element engageable with the outer face of a backbone, and telescopically related male and female parts carried by the respective elements and projecting from the respective elements for engagement with each other within a backbone.

6. A split ring device for use in ring type binders, said device comprising a ring element having a base portion engageable with the inner face of a backbone, an anchorage element engageable with the outer face of a backbone, and telescopically related male and female parts carried by the respective elements, the female part being carried by the anchorage element and being transversely slotted to receive the male part of the ring element.

7. A split ring device for use in ring type binders, said device comprising a ring element having a base portion engageable with the inner face of a backbone, an anchorage element engageable with the outer face of a backbone, and telescopically related male and female parts carried by the respective elements, the female part comprising a cavity in one of said elements, said element having a plate surface within which such cavity is extended.

8. A split ring device for use in ring type binders, said device comprising a ring element having a base portion engageable with the inner face of a backbone, an anchorage element engageable with the outer face of a backbone and telescopically related male and female parts carried by the respective elements, the said female part comprising a cavity within one of said elements, said last mentioned element having a back engaging surface into which said cavity extends and being provided with a flange extending said cavity beyond said surface.

9. The device of claim 5 in which said parts

are formed for non-rotatable slidable adjustment relative to each other and are in adhesive connection.

10. The combination with a ring element having binder engageable portions and an apertured tab adapted to be received through a binder so engaged, of a wedge member in the aperture of the tab and provided with detent means engaging the tab against its withdrawal.

11. A split ring element having a base portion provided with a socket in combination with an anchorage element having a stud engaged in the socket, said stud and base portion being formed for non-rotative sliding engagement with each other and being in adhesive connection.

12. A split ring binder element in combination with an anchorage element, one of said elements being provided with at least one stud and the other element being provided with at least one socket in which said stud is slidably adjustable, said elements having means interlockingly engaged to preclude rotation of the stud in the socket, together with means for maintaining the stud and socket in a predetermined position of sliding adjustment to fit a particular binder.

13. A binder ring for use with binders having flat backbones and with binders having concave backbones, said ring comprising a base having its lower surface flat at the mid portion of said base and thence beveled upwardly at each side, and a pair of curvilinear arms connected to said base adjacent its respective sides and having free tip portions in immediate proximity to each other above the center of the base, anchorage means applicable externally to a binder backbone, and means connected in part to said base at its mid portion and in part to said anchorage means for connecting said base to said anchorage means through a backbone, irrespective of the flat or concave form of the backbone.

14. A split ring for use in a looseleaf binder having a backbone, said ring comprising a base, a pair of crescent-shaped arms thereon, each of said arms progressively decreasing in cross section upwardly away from said base, and said base comprising means limiting the movement of apertured paper sheets downwardly upon the respective arms, and anchorage means applicable externally to a binder backbone, said base having centrally of its bottom surface a connecting element and said anchorage means having a cooperative connecting element, the respective elements being formed for slideable telescopic engagement, and said base having a lower surface at either side of its connecting element which is substantially flat and thence is obliquely beveled to the sides of the base.

JOHN J. SEELMAN.
